ELECTRICAL TRANSFORMER

Roger B. Kerr, Marblehead, Mass., assignor to General
Electric Company, a corporation of New York

Application December 22, 1955, Serial No. 39,426

Term of patent 14 years

(Cl. D26—15)

Fig. 1

Fig. 2

Fig. 4

Figure 1 is a perspective view showing the front and one end of an electrical transformer embodying my new design,

Figure 2 is a side elevation taken from the back of the transformer shown in Figure 1,

Figure 3 is an end elevation taken from the right of the transformer in Figure 1, and

Figure 4 is a plan view of the same.

The dominant features of my design reside in the portions shown in full lines.

I claim:

The ornamental design for an electrical transformer, as shown and described.
